(57) **CLAIM**

The ornamental design for a soldered mini-link mechanism, as shown and described.

DESCRIPTION

FIG. 1 is a front and right side perspective view of the first embodiment of a soldered mini-link mechanism show my new design;

FIG. 2 is a rear and left side view thereof;

FIG. 3 is a right side view thereof;

FIG. 4 is a left side view thereof;

FIG. 5 is a front view thereof;

FIG. 6 is a rear view thereof;

FIG. 7 is a cross-sectional view taken along line 7-7 of FIG. 5;

FIG. 8 is a cross-sectional view taken along line 8-8 of FIG. 6;

FIG. 9 is a cross-sectional view taken along line 9-9 of FIG. 6;

FIG. 10 is a front and right side perspective view of a second embodiment of a soldered mini-link mechanism;

FIG. 11 is a rear and left side perspective view thereof;

FIG. 12 is a right side view thereof;

FIG. 13 is a left side view thereof;

FIG. 14 is a front view thereof;

FIG. 15 is a rear view thereof;

FIG. 16 is a cross-sectional view taken along line 16-16 of FIG. 14;

FIG. 17 is a cross-sectional view taken along line 17-17 of FIG. 15; and,

FIG. 18 is a cross-sectional view taken along line 18-18 of FIG. 15.

The broken lines in FIGS. 1 to 18 are shown for the purpose of illustrating a structure of the environment, are for illustrative purposes only, and form no part of the claimed design.
